UNITED STATES PATENT OFFICE.

ANTON G. EYLES, OF CEDAR RAPIDS, IOWA, ASSIGNOR OF ONE-HALF TO JOHN H. LEE,
OF OAK PARK, ILLINOIS.

TEMPO-CONTROL DEVICE.

1,328,870.

Specification of Letters Patent. Patented Jan. 27, 1920.

Application filed August 19, 1916. Serial No. 115,804.

To all whom it may concern:

Be it known that I, ANTON G. EYLES, a citizen of the United States, residing at Cedar Rapids, in the county of Linn and State of Iowa, have invented a new and useful Improvement in Tempo-Control Devices, of which the following is a specification.

This invention relates to self-playing musical instruments, and particularly to means for controlling the time of the music.

The primary object is to provide a simple automatic controller which controls the speed of the motor, and which is associated with a tempo-indicator in such a manner that the time of the music may be readily set at a desired rate, either before the playing starts, or during the playing operation.

The invention is illustrated in its preferred embodiment in the accompanying drawings, in which—

Figure 1 represents a front elevational view of the music-roll-carrying mechanism, motor, and associated parts of a self-playing instrument, equipped with my improved tempo-regulating device; Fig. 2, a broken plan view of the automatic controller employed; Fig. 3, a broken front elevational view of the same; Fig. 4, a sectional view taken as indicated at line 4 of Fig. 2; Fig. 5, a broken view, diagrammatic in its nature, illustrating a modification; Fig. 6, a broken view, diagrammatic in its nature, illustrating a still further modification; and Fig. 7, a plan view of another modification.

In the construction illustrated in Figs. 1 to 4, inclusive, A represents the music-roll-carrying mechanism of a piano-player action or mechanism, for illustration; B, the motor thereof; C, the wind-chest, or suction-box; C', the governor pneumatic; C², the tempo-box; C³, the tempo-valve which controls the passage of air through the motor-tube C⁴; C⁵, the re-roll valve; D, an automatic controller connected with the valve C³ of the motor-control device; and D', a tempo-indicator having a member connected with the automatic controller, either directly, as illustrated in Figs. 1 to 4, inclusive, or as illustrated in Fig. 5, or indirectly, as indicated in Fig. 6.

The music-roll-carrying mechanism A is

supported on a frame A', in the usual manner. It is provided, as is usual, with a roller 1 for the music-roll, a roller 2 which serves as a take-up spool, and a tracker-bar 3 over which the music-sheet passes. Either the roller 2 or the roller 1 may be actuated, at will, through the medium of gear mechanism 4 actuated by the motor B, in a well understood manner.

The motor B, which is illustrated, is of the pneumatic type and is provided with a shaft 5, which actuates the gear mechanism 4.

The mechanism C, C', C², C³, etc., which is concerned with the variations of pressure in the motor-tube C⁴, whereby the motor is operated, need not be explained in detail. This mechanism may be of any desired type. The valve C³ forms a part of the motor-control device. It is associated with a graduated tempo-slot 6, and as the valve C³ is moved to close more of the slot 6, the speed of the motor is reduced.

The valve C³ is connected, by a rod 7, with a lever 8. The lever 8, in turn, is connected by a rod 9 with a hand lever 10 associated with what is usually known as the key-bed 11. The lever 10 is fulcrumed at an intermediate point, as indicated at 12. The lower end of the lever is connected with the rod 9 and is also connected with a rod 13. The rod 13 is also connected with the lower arm 14 of a vertical rock-shaft 14^a, whose upper end is equipped with an arm 14^b. The arm 14^b has connected therewith a rod 15, which extends parallel with the axes of the rollers 1 and 2 and slides through a guide 16, with which the frame A' is equipped a short distance below the plane of the roller 2.

The automatic controller D, in the form illustrated, comprises a shoe, or mounting, 17; a rock-member 18 pivoted in the mounting 17 at the point 18^a and having an actuating arm 18^b, and having also an arm 18^c, which forms an acute angle with the arm 18^b; a spring 19 interposed between a collar 19^a on the rod 15 and a perforate lug 19^b with which the shoe 17 is provided and through which the extremity of the rod 15 extends, said extremity being equipped with a collar 19^c; and a link 20, one end of which is connected, by a pivot or wrist-pin 21, with the extremity of the arm 18^c, and the other

end of which is provided with a rearwardly-turned perforate portion 22, through which the rod 15 extends, the portion 22 engaging a collar 23 secured adjustably on the rod 15 by means of a set-screw 24.

The shoe 17 has rearwardly extending arms 17^a adapted to bear lightly upon the horizontal surface of the frame-member A', below the roller 2. The shoe is provided, in alignment with the perforate lug 19^b, with a perforate lug, or socket, 25, which is equipped with a set-screw 26.

The tempo indicator D' comprises a tempo scale 27 secured to the frame member A'; and a pointer 28 associated therewith and carried by a rod 29, which is in alignment with the rod 15. The rod 29 has one end extending into the socket 25 and secured thereto by the set-screw 26. The rod 29 is mounted in guides 30 and 31 carried by the frame-member A'. Sufficient friction exists between the rod 29 and its guides and the shoe 17, and the surface against which it bears, to prevent accidental movement of the tempo-indicator member 28, with reference to the scale 27. This does not interfere, however, with the freedom of setting the indicator by means of a hand-lever 10.

The automatic governor D may be moved longitudinally with relation to the roller 2 in the operation of setting the tempo-indicator at a point to give the desired speed of the motor. As the music-sheet is wound upon the roller 2 during the playing operation, the diameter of the roller 2 is thereby increased. Were the motor to continue at its original speed, the surface speed of the music-roll would increase as the diameter increased. This is automatically compensated for, however, by the automatic controller D, whose arm 18^b has a rearwardly-turned portion disposed beneath the roller 2 and co-acting therewith, so that the rock-member 18 will be turned in its bearing in the shoe, or shiftable mounting, 17, thereby drawing the rod 15 to the left against the action of the spring 19. This movement causes the rock-shaft 14^a to turn in such direction as to move the arm 14 to the right, thus drawing the lever 8 to the position indicated by dotted lines in Fig. 1. The result is to automatically move the tempo valve C³ to the left, as indicated by the dotted lines, thus gradually closing the tempo slot 6 of the motor-controlling device.

The leverage is so determined that as the diameter of the roller 2 increases, the valve C³ will be automatically shifted in such manner as to slow down the motor gradually and in just sufficient degree to maintain a constant surface speed at the periphery of the gradually enlarging music-roll which is being wound upon the roller 2. It is possible, however, to shift the tempo-indicator 65 and likewise the tempo-valve C³ during the

playing operation, by moving the hand-lever 10. Thus, the pointer 28 may be shifted from the position which it occupies at any given instant to any other point on the scale 27, while the playing operation is in progress, so that the tempo may be manually changed when desired, without stopping the operation of the mechanical player. In Figs. 1 and 4, the dotted lines 2^a represent the enlarged music-roll; and in Fig. 4, the rock-arm 18^b is shown in the depressed position which it occupies after having been depressed by the enlarged music-roll. The portion of the arm 18^b which extends beneath the roller 2 is rounded, or of circular cross-section, so that there will be a smooth contact with the music-sheet, and the automatic controller D may be readily shifted longitudinally with respect to the roller 2.

In the modification shown in Fig. 5, the construction is the same as that described, except that the rod 29 which carries the indicator pointer 28 is extended to the left and connected with one arm of a vertical rock-shaft 32, whose lower end is equipped with an arm connected by a link 33 with a hand-lever 34. In this modification, the rod 29 is connected, as before, with the automatic regulator D, so that the hand-lever 34 is indirectly connected with the lever 8. In such case, the rod 13 may be connected directly to the lever 8 and the hand-lever 10 may be dispensed with. The lever 34 may be employed to adjust the tempo, the motion being communicated through the rod 15 and other connections with the valve C³. The automatic controller would work in the same manner as before, while the lever 34 and the indicator pointer 28 would remain stationary, unless manually adjusted, by means of the lever 34.

In the modification illustrated in Fig. 6, D² represents an automatic controller of the same construction as the controller D, but which is not directly connected with the rod 29^a which carries the indicator pointer 28^a. The rod 29^a connects with a rock-shaft 32^a, which is connected, by a link 33^a, with the lever 8. In this modification, the indicator pointer 28, as well as the hand-lever 10, would automatically shift gradually under the influence of the automatic controller D². It would nevertheless be possible to shift the indicator during the playing operation, by means of the lever 10, from its point at any given instant, to manually change the tempo, it being understood that the valve C³ would be shifted at the same time.

Referring again to Fig. 2, it will be noted that the tension of the spring 19 may be adjusted by the adjustable collar 19^a; also, the point of connection of the link 20 with the rod 15 may be adjusted by means of the adjustable collar 23, this being done without affecting the tension of the spring 19.

In some machines, the take-up roller 2 is placed closer to the frame-member A' than is the case in other machines; hence the desirability of employing an adjustable connection between the rock-lever 18 and the tempo-rod 15.

The advantages of my invention will at once be appreciated by those skilled in the art. At the present time, a speed-regulating device for mechanical piano-players is not in use, so far as I am aware, although the need for such a device is very great. The present device is a very simple device which effectively accomplishes the purpose. The invention can be quite readily adapted to the various makes of piano-player actions. In the illustration given in Fig. 1 is shown one well-known form of piano-player action. In this case, the tempo mechanism has not been altered, except that the tempo-indicator has been moved to the left and the automatic controller D has been interposed between the indicator and the rod 15. In effect, the rod 29 is an extension of the rod 15, but with the automatic controller D interposed between the sections of the tempo-rod, so that while the rod-section 29 which carries the indicator-pointer may remain stationary during the playing operation, the rod-section 15 will be drawn to the left as the diameter of the music-roll increases. This amounts to making the tempo-rod of automatically varying length and dependent upon the variation of the diameter of the music-roll, the indicator section of the rod normally remaining stationary, but the whole device, nevertheless, being shiftable through the medium of the lever 10 to enable the tempo to be arbitrarily set preparatory to playing, or arbitrarily adjustable during the playing operation. In the modification shown in plan in Fig. 7, the automatic controller D² is housed in a separate compartment E a short distance from the location of the take-up roll 2; and the arm 18^b of the controller, instead of bearing directly against the music-roll, is actuated by an added member of the controller in the form of a rock-shaft 35 which has an arm 35^a that bears against the music-sheet as it wraps upon the roll 2. The member 35, which has its axis parallel with the roll 2, is provided with a wide crank portion 35^b adapted to engage the arm 18^b, regardless of the position of the controller D² as it may be shifted manually in controlling the tempo. The pointer 28^b of the indicator is carried by a rod 29^b connected with the controller D². The automatic controller operates a tempo-rod 15^a, which connects with the arm 36 of a vertical rock-shaft 36^a, which has connections (not shown) at its lower end for shifting the valve which controls the motor; and these connections may,

if desired, connect with the manual shifting lever, corresponding with the lever 10 in Fig. 1. If desired, however, the rod 29^b may be extended and joined by connections in the manner shown in the case of the rod 15, in Fig. 1, to a manual controlling lever, such as 10.

Various changes in details of construction and arrangement within the principle of the invention may be made; hence no unnecessary limitation should be understood from the foregoing detailed description, but the appended claims should be construed as broadly as permissible, in view of the prior art.

What I regard as new, and desire to secure by Letters Patent, is:

1. In a self-playing musical instrument, the combination with music-roll-carrying mechanism, a motor, a tempo-indicator and motor-control device, of an automatic controller connected with both the indicator and the motor-control device and having an actuating member co-acting with a roller of said music-roll-carrying mechanism.

2. In a self-playing musical instrument, the combination with music-roll-carrying mechanism, a motor, a tempo-indicator and motor-control device, of an automatic controller connected with both the indicator and the motor-control device and having a yieldingly-held actuating member co-acting with a roller of said music-roll carrying mechanism.

3. In a self-playing musical instrument, the combination with music-roll-carrying mechanism, a motor for actuating the same, a slideable tempo-rod disposed parallel with a roller of the music-roll-carrying mechanism and equipped with an indicator member and a motor-control device, of an automatic controller connected with said rod and also connected with the motor-control device and having an actuating member co-acting with said roller.

4. In a self-playing musical instrument, the combination with music-roll-carrying mechanism, a motor for actuating the same, a slideable tempo-rod disposed parallel with a roller of the music-roll-carrying mechanism and equipped with an indicator member and a motor-control device, of an automatic controller having an actuating member co-acting with said roller, connections between the motor-control device and both the automatic controller and said rod, and a manual controlling lever permitting arbitrary adjustment of the tempo either preparatory to or during the playing operation.

5. In a self-playing musical instrument, the combination of music-roll-carrying mechanism, a motor for actuating the same, a rod slideable parallel with a roller of said mechanism and equipped with a tempo-in-

dicator member, another rod parallel with said roller, a lever connected with said rods and having an arm co-acting with said roller, a spring tending to hold said arm in engagement with said roller, a motor-control device, connections between said motor-control device and said rods, and a hand-lever adapted to arbitrarily control the motor-control device and to arbitrarily shift said rods.

- 10 6. In a self-playing musical instrument, the combination with music-roll-carrying mechanism, a motor for actuating the same, a motor-control device having connections 15 equipped with a readily accessible hand-control for arbitrarily regulating the tempo, a bodily shiftable automatic controller joined to said connections and comprising an actuating member co-acting with a roller 20 of the music-roll-carrying mechanism, and a spring tending to hold said actuating member in engagement with the music-roll.

7. In a self-playing musical instrument, the combination of music-roll-carrying 25 mechanism, a motor for actuating the same, a motor-control device having connections equipped with a readily accessible hand-control for arbitrarily regulating the tempo, of an automatic controller comprising a shoe 30 shiftable longitudinally with respect to a roller of the music-roll-carrying mechanism, an actuating member carried by said shoe and co-acting with said roller, connections between said actuating member and said 35 first-named connections, and a spring shiftable with said shoe and serving to maintain said actuating member in engagement with the music-roll.

8. In a self-playing musical instrument, 40 the combination of music-roll-carrying mechanism, a motor, a pair of rods slidable parallel with relation to a roller of said music-roll-carrying mechanism, a tempo-indicator member carried by one of said 45 rods, a mounting secured to said last-named rod and shiftable therewith and having a loose connection with the other rod, a lever carried by said mounting and having an actuating member co-acting with said roller, 50 a link connecting said lever with said other rod, a spring opposing the action of said lever, a motor-control device, connections between the motor-control device and said other rod, and a manual shifting lever for 55 arbitrarily adjusting the tempo.

9. In a self-playing musical instrument, the combination of music-roll-carrying mechanism, a motor, a normally stationary indicator-rod, an automatically shifting rod, 60 a motor-control device connected with said last-named rod, and an automatic controller interposed between said rods and controlled by the music-roll and serving to automatically vary the combined length of said rods.

- 65 10. In a self-playing musical instrument,

the combination of music-roll-carrying mechanism, a motor, a normally stationary indicator-rod, an automatically shifting rod, a motor-control device connected with said last-named rod, an automatic controller interposed between said rods and controlled by the music-roll and serving to automatically vary the combined length of said rods, and a manual shifting lever adapted to arbitrarily set the tempo.

75

11. In means of the character set forth, the combination with the take-up roller of music-roll-carrying mechanism, and a tempo-rod, of a mounting slidable longitudinally with relation to said roller, and means carried by said mounting and controlled by the diameter of the music-roll for automatically varying the position of said tempo-rod.

80

12. In means of the character set forth, the combination with the take-up roller of music-roll-carrying mechanism, of a mounting movable parallel with said roller, a tempo-rod parallel with said roller and yieldingly connected with said mounting, a lever carried by said mounting and connected with said tempo-rod and controlled by the diameter of the music-roll, a pneumatic motor, a valve controlling the speed of said motor, connections between said valve and said tempo-rod, and a manual lever adapted to arbitrarily change the position of said valve.

85

13. The combination of the take-up roller of music-roll-carrying mechanism, a pneumatic motor, a valve controlling the speed of said motor, a mounting movable parallel with said roller, a lever carried by said mounting and controlled by the diameter of the music-roll, a tempo-rod loosely connected with said mounting, a spring engaging said mounting and yieldingly holding said rod, a link connecting said lever to said rod, connections between said valve and said rod, and a manual lever joined to said connections and adapted to arbitrarily set the tempo.

90

14. The combination with the take-up roller of music-roll-carrying mechanism, of a pneumatic motor, a valve controlling the speed of said motor, a mounting slidable parallel with said roller, a tempo-rod loosely connected to said mounting, an actuating member connected with said rod and controlled by the diameter of the music-roll, 110 connections between said valve and said rod, a rod connected with said mounting and carrying an indicating member, and a manual shifting lever for arbitrarily adjusting the tempo.

115

15. The combination with the take-up roller of music-roll-carrying mechanism, of a pneumatic motor, a valve controlling the speed of said motor, a mounting movable parallel with said roller, a tempo-rod loosely 120

125

130

- connected to said mounting, means carried by said mounting and controlled by the diameter of the music-roll for automatically moving said rod, a vertical rock-shaft connected with said rod, link-and-lever connections between said rock-shaft and said valve, and a manual lever associated with said link-and-lever connections and adapted to arbitrarily adjust the tempo.
16. The combination with the take-up roller of music-roll-carrying mechanism, of a pneumatic motor, a valve controlling the speed of said motor, a mounting movable parallel with said roller, a lever carried by said mounting and controlled by the diameter of the music-roll, a rod loosely connected to said mounting, adjustable connections between said lever and said rod, and link-and-lever connections between said rod and the said valve.
17. The combination with the take-up roller of music-roll-carrying mechanism, of a pneumatic motor, a valve controlling the speed of said motor, a mounting movable parallel with said roller, a lever carried by said mounting and controlled by the diameter of the music-roll, a rod loosely connected to said mounting, adjustable connections between said lever and said rod, link-and-lever connections between said rod and the said valve, and a manual lever associated with said link-and-lever connections and adapted to arbitrarily adjust the tempo.
18. The combination with the take-up roller of music-roll-carrying mechanism, of a pneumatic motor, a valve for regulating the speed of said motor, a tempo scale parallel with said roller, a rod parallel with said roller and equipped with a pointer associated with said scale, a second rod parallel with said roller, a mounting slidable parallel with said roller, an actuating member mounted thereon and controlled by the diameter of the music-roll and connected with said second-named rod, link-and-lever connections between said second-named rod and said valve, and a manual shifting lever adapted to shift said rods and said valve.
19. In means of the character set forth, the combination with a take-up roller, a 50 pneumatic motor for actuating the same, and a valve controlling the speed of the motor, of a tempo rod parallel with said roller and comprising two slidable movably related sections, a tempo indicator carried by 55 one of said sections, means for guiding said section and normally preventing movement thereof, means interposed between said sections and controlled by the music roll for automatically moving the other section, connections between said last-named section and said valve for transmitting motion to said valve, and manual shifting means whereby said rod-sections and said valve may be shifted to arbitrarily adjust the 60 tempo.
20. In a self-playing musical instrument, the combination with music-roll-carrying mechanism, a motor, a tempo-indicator and a motor-control device, of an automatic controller connected with both the indicator and the motor-control device and comprising a shiftable tempo-rod-actuating member and its mounting, and a rock-member adapted to actuate said tempo-rod-actuating member 70 and having an arm co-acting with a roller of said music-roll-carrying mechanism.
21. In a self-playing musical instrument, the combination with music-roll-carrying 80 mechanism, a motor, a tempo-indicator rod, and motor-control device, of an automatic controller comprising an actuating arm co-acting with a roller of said music-roll-carrying mechanism, and a shiftable mounting 85 on which said arm is mounted and which has operative connections with said motor control device and said tempo-indicator rod.

ANTON G. EYLES.
